CLAIM

I claim the ornamental design for a rear combination lamp for an automobile, as shown and described.

DESCRIPTION

FIG. 1 is a front perspective view for a “rear combination lamp for an automobile” showing our new design,

FIG. 2 is a rear perspective view thereof,

FIG. 3 is a front view thereof,

FIG. 4 is a rear view thereof,

FIG. 5 is a top view thereof,

FIG. 6 is a bottom view thereof,

FIG. 7 is a left-side view thereof; and,

FIG. 8 is a right-side view thereof.
